JEWELRY PIN OR THE LIKE

Eugene E. Bertolli, West Cheshire, Conn., assignor to
The Napier Company, Meriden, Conn., a corporation of Connecticut

Application December 28, 1954, Serial No. 33,716

Term of patent 14 years

(Cl. D45—19)

FIG. 2.

Fig. 1 is a plan view on an enlarged scale of a jewelry pin, showing my new design.

Fig. 2 is a perspective view thereof showing portions of the reverse side of the pin.

I claim:

The ornamental design for a jewelry pin or the like, substantially as shown.
